Primary Examiner — Richard E Chilcot*(74) Attorney, Agent, or Firm* — Wenderoth, Lind & Ponack, L.L.P.(57) **CLAIM**

The ornamental design for a boring machine with casing driver, as shown and described.

DESCRIPTION

1. Boring machine with casing driver

1.1 : Front

1.2 : Back

1.3 : Left

1.4 : Right

1.5 : Top

1.6 : Cross sectional

(Continued)

The boring machine with casing driver is used for such as excavating the ground, driving piles, to perform pile foundation work; A bottom view is omitted because the article is a heavy object.

1 Claim, 6 Drawing Sheets
